Howard Morrison

UNITED STATES PATENT OFFICE.

CHARLES S. MORRISON, OF ELKINS PARK, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

TOGGLE.

Application filed April 27, 1928. Serial No. 273,352.

- My invention relates to certain improvements in toggles used in stretching leather on frames. In this type of toggle there is a hook at the back of the toggle which extends through one of the perforations in a supporting plate or through the meshes of a wire screen, so that when the toggle engages the leather the leather will be drawn tight and the hook can engage the frame.
- 10 An object of the present invention is to provide means for causing the tension of the leather to actuate the gripping mechanism, so that as the leather shrinks, the grip of the toggle will be correspondingly increased.
- 15 The invention also relates to certain details of construction of parts which will be fully described hereinafter.

In the accompanying drawings:

- Figure 1 is a side view of a toggle made 20 in accordance with my invention;
- Fig. 2 is a plan view;
- Fig. 3 is a sectional view, longitudinally on the line 3—3, Fig. 2;
- Fig. 4 is a front end view of the toggle;
- 25 Fig. 5 is a rear end view;
- Fig. 6 is a detached perspective view of the upper jaw;
- Fig. 7 is a detached perspective view of the upper jaw operating lever;
- 30 Fig. 8 is a detached perspective view of the lower jaw; and
- Fig. 9 is a detached perspective view of the operating plate of the lower jaw.

- Referring to the drawings, 1 is the body 35 of the toggle which is made of pressed sheet metal having a base 2, integral sides 3—3, and a looped rear section 4 which forms a handhold for the operator when using the toggle.
- 40 The upper portion of the handhold 4 is cut away at 5 to form lateral projections 6, which extend through perforations in the side members 3—3 and are riveted as shown so as to rigidly secure the upper portion of the handhold to the sides.

- 45 7 is an upper jaw mounted on a transverse pivot pin 8 which extends through two side members 3—3, the ends being riveted as shown in Fig. 2. The upper jaw is U-shaped 50 in cross-section, and mounted on the pivot pin 8 is a coil spring 9, one end of which rests upon the jaw as shown in Fig. 3 and the other end bent to extend through a hole 10 in one of the side members 3.
- 55 The jaw 7 is held in the open position as

shown in Fig. 3 by the spring 9, and is closed by an operating lever 11 shown in Fig. 7. The lever 11 is pivoted on a cross-bar 12 which extends from one side member to the other, the lever being provided with a 60 roller 13 mounted on a cross-bar 14 extending from one side flange 15 of the lever to the other side flange, as clearly shown in Fig. 7. This cross-bar rests under the heel of the jaw 7 and when the lever is moved from its raised 65 position shown in Fig. 3 to the position shown in Fig. 1, it closes the jaw 7 and holds it in its closed position as shown in Fig. 1. The lower jaw 16 is shaped as shown in Fig. 8 and has a serrated surface 17, the rear 70 end of the jaw being rounded as shown at 18 so as to prevent the jaw cutting the leather when pressure is applied. The jaw has side members 19 which are perforated for the passage of a pivot pin 20. The serrated surface of the jaw is eccentric to this pivot, so that when it is turned on the pivot it will 75 grip the leather when the upper jaw 7 is closed.

A coil spring 21 is mounted on the pin 20. 80 One arm of this pin rests against the underside of the lower jaw 16 while the other end of the spring rests against a plate 22 which is mounted on the base 2 of the body portion.

The plate 22 is notched at each side as 85 shown at 23, and extending into each notch is a tongue 24 which projects from each side 19 of the lower jaw 16. These tongues preferably extend into slots 25 in the base 2 of the toggle.

90 Mounted on the cross-bar 12 is a hook 26. This hook extends through a slot 27 in the plate 22 and through a slot 28 in the base 2 of the body portion. The hook is shaped as shown in Fig. 3, and when the toggle grips 95 the leather b, the tongue 26 is passed through one of the perforations in a supporting plate a as shown in Fig. 1. As pressure is applied the pull of the leather tends to place pressure upon the hook 26, the hook in turn 100 moving the plate 22, and as the plate 22 is engaged by the tongues 24, the tension will turn the lower jaw on its pivot and increase its pressure upon the leather, thus increasing the grip of the toggle. The leather can be 105 quickly released from the toggle by turning the lever 11 to the position shown in Fig. 3, when the upper jaw will be raised.

I claim:

1. The combination in a toggle, of a body 110

portion; an eccentric lower jaw and an upper jaw; means for clamping leather between the two jaws; a hook pivotally mounted on the body portion and extending 5 therefrom; and a plate engaged by the hook and by the lower jaw, so that when tension is applied to the leather the hook will move the lower jaw through the plate.

2. The combination in a toggle, of a body 10 portion forming a handhold and having side members; an upper jaw pivotally mounted on said side members; an eccentric lower jaw pivotally mounted on the side members; a spring tending to close the jaw against the upper jaw; and a lever also pivotally mounted on said side members and arranged to bear upon the heel of the upper jaw to force it towards the lower jaw.

3. The combination in a toggle, of a body 20 portion having side members and a bent handhold attached at its free end to the side members; an eccentric lower jaw pivoted to the side members; an upper jaw also pivoted to said side members located opposite the lower jaw; a lever pivoted to the side members and having a roller arranged to bear against the heel of the upper jaw and close it upon the leather inserted between the two jaws; a spring tending to open the upper jaw; and a spring tending to close the lower jaw.

4. The combination in a toggle, of a body portion having side members and a bent handhold attached at its free end to the

side members; an eccentric lower jaw pivoted to the side members; an upper jaw also pivoted to said side members located opposite the lower jaw; a lever pivoted to the side members and having a roller arranged to bear against the heel of the upper jaw and close it upon the leather inserted between the two jaws; a spring tending to open the upper jaw; a spring tending to close the lower jaw; a loosely mounted hook extending through a slot in the body portion; and a slotted plate through which the hook extends, the lower jaw being connected to said plate and arranged to be moved by the hook through the medium of the plate when tension is applied to the leather gripped between the jaws.

5. The combination in a toggle, of a body portion; a serrated lower jaw eccentrically mounted on the body portion and having a projecting tongue; a notched plate 55 through which the tongue projects; said plate being arranged to slide on the body portion; a pivoted hook extending through a slot in the plate and through a slot in the body portion; a pivoted upper jaw; and a lever pivoted to the side members of the body portion and arranged to bear against the heel of the upper jaw, the bearing of the lever against the upper jaw being such that when the lever is closed the upper jaw will 60 be held in its closed position.

CHARLES S. MORRISON.
